UNITED STATES PATENT OFFICE.

OLIE T. NELSON, OF TACOMA, WASHINGTON.

BOILER.

1,235,916.

Specification of Letters Patent.

Patented Aug. 7, 1917.

Application filed October 30, 1916. Serial No. 128,357.

To all whom it may concern:

Be it known that I, OLLIE T. NELSON, a citizen of the United States, and a resident of Tacoma, in the county of Pierce and State 5 of Washington, have invented certain new and useful Improvements in Boilers of which the following is a full, true, and exact specification.

My invention relates to boilers and has 10 for its principal object to improve upon the construction of my boiler as outlined in my previous Patent #1196140 and my pending application #44763, filed August 10th, 1915, in that the baffle plate referred to in my 15 previous patent is made with an incline toward the center of the boiler for the purpose of allowing the sediment which is deposited from the water in the boiler to be washed from the baffle plate. In my previous construction with the baffle plate sediment was 20 found to accumulate on the plate with the result of a deposit of scale. At the present time I am manufacturing boilers with the plate inclined as shown in this application 25 and in this way have obviated the objections to my previous constructions. Another object of this application is to provide an improved down draft fire box or steel boiler setting which embodies water cooled grates 30 of novel construction.

Other objects will appear as my invention is more fully explained in the following specification, illustrated in the accompanying drawing and pointed out in the appended 35 claims.

In the drawings Figure 1 is a side elevation of my boiler shown in position upon my improved setting with parts broken away. Fig. 2 is a fragmentary plan view 40 of the water cooled grate of Fig. 1. Fig. 3 is an enlarged cross sectional view of one of the water cooled grate bars.

Referring more particularly to the drawings, numeral 1 indicates a fire tube boiler 45 having an offset portion at its rear end. The offset portion is semi-circular and is cut diametrically across the lower half of the boiler. The portion of the boiler between the offset semi-circular end and semi-circular 50 portion which is not offset is closed by an inclined baffle plate 2 which is integral with the rear head of the boiler. Tubes 3 are connected in the rear end of the boiler as in my previous patent. I prefer to incline 55 the plate 2 in order that any sediment which is deposited from the water in the boiler will

be gradually worked down along the inclined plates and dropped adjacent to a blow-off pipe 4. I have found that the circulation of the water in the boiler is sufficient 60 to wash the sediments from an inclined plate, whereas it will deposit on the horizontal plane with the result that the plates have a tendency to burn out quickly, due to improper cooling. My improved boiler setting 65 and fire box embodies the down draft feature which has an upper grate and a lower grate. The boiler setting 5 consists of metal plates in special relationship to each other and between which the water in the boiler freely 70 circulates. The setting is provided with the usual grates 6 and with my improved water cooled upper grate bars 7 upon which the fuel is first deposited, and through which it drops down upon the lower grate 6 during 75 the process of burning. The grate bars 7 are tubular and are closed at their outer end 8 while at the other end they are screwed into flanges upon the boiler setting 5. A circulating plate 9 divides each bar 7 along 80 its horizontal diameter but does not reach as far forward as the closed end. The circulating plate 9 projects somewhat into the setting 5 and is bent down as at 10 in order to cause the rising water in the setting to 85 flow into the grate bar beneath the plate and after it is further heated by the fire beneath the grate bar it will circulate around the outer end of plate 9 and backing into the setting about said plate, thereby at all times 90 keeping the grate bar cool and quickly heating the water. I also provide a water cooled back 11 which is of similar construction as the boiler setting and which is positioned 95 transversely the setting and adjacent the bottom of the boiler and at a point just back of the upper grate bar 7. My boiler fire box, it will be understood, is of the down draft type and has proven very successful 100 in actual tests.

While I have shown a particular form of embodiment of my invention, I am aware that many minor changes therein will readily suggest themselves to others skilled in the art without departing from the spirit 105 and scope of the invention, and I therefore desire to avoid being limited to the exact form shown and described. Having described my invention, what I claim as new and desire to protect by Letters Patent, is— 110

1. In combination, a horizontal boiler having its rear upper portion extended beyond

the lower rear portion, the bottom plate connecting the upper and lower portions being forwardly inclined, tubes extending the full length of the boiler above the plate, a second set of tubes extending from the lower shorter portion of the rear of the boiler to the front end of said boiler, a drain tube at the bottom of the rear end of the short portion of the boiler, whereby sediment will slide down the inclined bottom plate to the open end of the drain tube to be carried off, and a boiler setting on which the front end of the boiler is supported and the rear upper extended end of said boiler is connected.

2. In combination, a hollow boiler setting, hollow grate bars at the forward end of the setting, a hollow baffle plate in rear of and above the hollow grate, a lower grate below the hollow grate bars, a bridge wall at the rear of the lower grate, a boiler supported by the hollow boiler setting, the rear upper portion of the boiler being extended beyond the rear lower portion and connected by a forwardly inclined plate, tubes extending from the rear upper end to the front of the boiler, tubes extending from the rear lower portion to the front of the boiler, a drain tube communicating with the bottom of the boiler adjacent the rear lower end and extending through the setting, whereby sediment will fall from the inclined plate to the

open end of the drain tube, the displaced upper and lower portions of the rear end of the boiler and the forwardly inclined plate forming a pocket for the products of combustion, the inclined plate acting as a deflector to direct said products of combustion downwardly to the lower set of tubes. 35

3. In combination, a boiler setting, grate bars at the forward end of the setting, a 40 baffle plate in rear of and above the grate, a lower grate below the first mentioned grate, a bridge wall at the rear of the lower grate, a boiler supported by the setting, the rear upper portion of the boiler being extended 45 beyond the rear lower portion and connected by a forwardly inclined plate, tubes extending from the rear upper end of the front of the boiler, tubes extending from the rear lower portion to the front of the boiler, a 50 drain tube communicating with the bottom of the boiler adjacent the rear lower end and extending through the setting, whereby sediment will fall from the inclined plate to the open end of the drain tube, the displaced 55 upper portion of the rear end of the boiler and the forwardly inclined plate forming a pocket for the products of combustion, the inclined plate acting as a deflector to direct said products of combustion downwardly to 60 the lower set of tubes.

OLLIE T. NELSON.
